PACKER AND SETTING TOOL

Ernest L. Barker, Houston, Tex.

Application December 23, 1935, Serial No. 55,754

7 Claims. (Cl. 166—10)

This invention relates to a packer and setting tool.

An object of the invention is to provide in a packer and setting tool, novel means for anchoring the setting string to the packer support, the anchoring means being of such construction that the same may be readily released and withdrawn to the ground surface preparatory to setting the packer.

10 In the process of setting a packer between the upper end of the liner, to which the screen is attached, and the outer casing the screen and packer and setting tool are attached to the lower end of the setting string and the screen is thus let down into the well. It is desirable, if not necessary, that the setting string be interlocked with the packer support during this letting-in process, so that the packer will not be prematurely expanded. After the screen has been set 15 in the well, it is then necessary to release the locking means to permit the setting tool to operate and expand the packer, and it is desirable that the operator may know definitely that the interlocking means have been released before it 20 is attempted to set the packer, as otherwise it cannot be definitely ascertained whether the packer has been set or not, or whether the setting string has been released from the packer support when it is desired to withdraw the string. It is 25 the prime object of this invention to provide interlocking means between the setting string and packer support that may be released and withdrawn to the derrick floor, so that the operator will have definite knowledge that the setting 30 string has been released from the packer support, whereupon the packer may be set and the setting string withdrawn without danger of withdrawing the packer with it.

Another object of the invention is to provide 40 in apparatus of this character, a novel type of wash pipe construction.

With the above and other objects in view, the invention has particular relation to certain novel features of construction, operation, and arrangement of parts, an example of which is given in 45 this specification and illustrated in the accompanying drawings, wherein:—

Figure 1 shows a fragmentary side elevation, partly in section of the upper end of the apparatus, showing the packer collapsed.

Figure 2 shows a vertical sectional view of an intermediate portion of the apparatus, showing the means for locking the setting string to the 55 packer support.

Figure 3 shows a fragmentary side view, partly in section, of the lower end of the apparatus.

Figure 4 shows a side elevation, partly in section, of the complete apparatus, showing the setting string locked with the packer support to maintain the packer collapsed.

Figure 5 shows a side view, partly in section, of the complete apparatus, showing the packer expanded.

Figure 6 shows a cross-sectional view taken on the line 6—6 of Figure 5, and,

Fig. 7 shows a cross-sectional view taken on the line 7—7 of Figure 4.

Referring now more particularly to the drawings wherein like numerals of reference designate the same parts in each of the figures. The numeral 1 designates a well casing set in a well. The numeral 2 designates a screen which is to be set in the well bore opposite the oil bearing strata.

Attached to the lower end of the screen there is the set shoe 3, of conventional construction, having the back pressure valve 4 of any preferred form.

Within the screen 2 there is the tubular wash pipe seat 5 which is supported by the shoe 3 and attached to the upper end of which is the tubular nipple 6, whose upper end carries the tubular wash pipe guide 7.

Secured to the upper end of the screen 2 there is an elongated special coupling 8 having the inside annular groove 9, and also having the inside ring-like packing 10, 10 above and beneath said groove.

A tubular packer body 11 is attached, at its lower end, to the upper end of the coupling 8. Around this packer body there is an expansible packer 12, whose lower end is seated on an external annular seat 13 on the body, and whose upper end abuts the ring 14 which is secured around the tubular slip support 15.

The upper end of the packer body has the external downwardly pitched ratchet teeth 16 and depending from the slip support are the expandable slips 17 which fit within the packer 12, and around the upper end of the body 11, and whose inner sides have the ratchet teeth 18 arranged to engage the teeth 16. Surrounding the upper end of the packer body and located beneath the slip 17 and within the packer 12 there is a downwardly tapering wedge ring 19, having a purpose to be hereinafter explained.

The screen 2, coupling 8 and body 11 form a packer support.

The numeral 20 designates the setting string through which the assembly may be lowered into

the well. At its lower end this setting string has an elongated relatively thick coupling 21, having oppositely arranged side slots 22, 22, and attached to the lower end of the coupling 21 is the reducing nipple 23. Depending from this nipple there is a wash pipe 24, whose lower end telescopes into the upstanding nipple 6.

Within the coupling 21 there is a head 25, whose lower end is bifurcated, forming the fingers 10 26, 26. Between these fingers are the dogs 27, 27, whose lower ends are outwardly turned in opposite directions. These dogs are pivoted on the cross-pin 28 and their inner ends are upwardly turned and provided with notches 29 which coincide when the dogs are in active position.

There is a locking rod 30, axially movable through the head 25 and whose lower end is formed with a latch 31 adapted to engage in the notches 29 to lock said dogs in said active position. A coil spring 32 is housed within the head 25 and presses against an external shoulder 33 on the rod 30, to maintain the latch in said locking position.

When the apparatus is assembled preparatory to lowering the screen and packer into the well the dogs 27 are projected through the slots 22 and into the groove 9, and are locked in such position by the latch 31, whereby the packer support and packer will be suspended from the setting string while being lowered into the well, and whereby the setting string will be prevented from moving downwardly relative to the packer support and prematurely setting the packer.

The packing 10, 10, above and beneath the dogs, 35 protect the dogs from sand, grit and the like from the surrounding mud laden fluid in the well, so that sand and like cannot pack around said dogs or collect within the head 25 to prevent the ready release of the dogs.

40 The groove 9 has the oppositely arranged abutments 34, 34, and in case it may be desired to rotate the packer support and packer while going into the well, the setting string may be rotated and the dogs will engage said abutments to rotate 45 the packer support and packer.

When the screen is landed on bottom, and it is desired to release the setting tool, an over-shot, or grapple of conventional construction, may be lowered down through the string 20 and 50 engaged over the conical shaped head 35 of the rod 30 and upon an upward pull the latch 31 will first be released and thereafter the head 25 will be elevated causing a withdrawal of the dogs 27 from the groove 9, and the locking device may 55 then be withdrawn from the well to the derrick floor, and the operator will know definitely that the setting string has been released from the packer support.

The string 20 may then be lowered and the 60 enlarged setting nipple 35 thereon will first engage the upper end of the slip support 15, and will move said support and the slip downwardly and the nipple will then engage the ring 14 forcing the same downwardly and expanding the 65 packer 12. As the packer is expanded the slips 17 will move downwardly between the packer 12 and the packer body 11 and the wedge ring will move downwardly in advance of the slips, thus gradually forcing the packer outwardly to insure 70 the free downward movement of the slips and to prevent the slips from injuring the packer. The packer 12 will thus be expanded closely against the casing 1 to form a fluid-tight joint therewith as shown in Figure 5.

75 When the packer is expanded, the slips 17 will

engage the teeth 16 of the packer body 11 and maintain the packer in expanded position.

Before the packer is set it is desirable to wash the screen and clean water may be forced down through the setting string and on down through the wash pipe 24 and out of the back pressure valve 4 and then up around the screen and up through the casing past the packer to the ground surface. The packer is then set as above explained, and the setting string, setting tool, and wash pipe may then be withdrawn from the well.

What I claim is:

1. In combination, a packer support, an expandable packer thereon, a setting string, a releasable device for locking the string to the support, said locking device, upon its release, being withdrawable, through the string.

2. In combination, a packer support adapted to be lowered into a well, a packer on the support, a tubular setting string having means thereon to expand the packer upon lowering of the string relative to the support, a device for locking the string to the support, said locking device being releasable and withdrawable through the string to permit downward movement of the string to effect expansion of the packer.

3. In combination, a tubular packer support adapted to be located in a well and having valve means at its lower end, a tubular upstanding wash pipe seat in the support above the valve means, a packer on the support, a tubular setting string, releasable means for connecting the string to the support, a wash pipe attached to the string and whose lower end has a telescoping relation with the wash pipe seat, said string and wash pipe being movable downwardly, upon release of said connecting means, an expandable packer on the support, means on the string effective to expand the packer upon such downward movement, said releasable connecting means, upon release thereof, being withdrawable through the string.

4. A packer and setting tool comprising a tubular support adapted to be set in a well, an expandable packer around the support, a tubular setting string, a releasable locking device within the string and in engagement with the support whereby the string may be locked against downward movement relative to the support, means on the string engageable with the packer and effective to expand the packer upon such downward movement of the string, said locking device being withdrawable as a unit through the string.

5. A packer and setting tool comprising a tubular support adapted to be set in a well, an expandable packer around the support, a tubular setting string, a releasable locking device within the string and in engagement with the support whereby the string may be locked against downward movement relative to the support, means on the string engageable with the packer and effective to expand the packer upon such downward movement of the string, said locking device being withdrawable as a unit through the string, and means for maintaining the packer expanded.

6. A packer and setting tool comprising a tubular support adapted to be set in a well, an expandable packer around the support, a tubular setting string, a releasable locking device within the string and in engagement with the support whereby the string may be locked against downward movement relative to the support, means on the string engageable with the packer and effective to expand the packer upon such downward movement of the string, said locking device being withdrawable as a unit through the string, said locking device be-

ing withdrawable as a unit through the string, said string and packer expanding means being withdrawable from the well upon release of said locking device, and means for maintaining the packer expanded.

5 7. In an apparatus of the character described, an outer and an inner pipe, spaced packings between the pipes, the outer pipe having an inside recess between said packings, a radially movable dog in the inner pipe engageable in the recess to

lock the pipes against relative longitudinal or rotary movement in either direction, means mounted in the inner pipe and operatively connected with the dog and effective to lock said dog in said engaged position, said means being releasable to permit disengagement of the dog and being withdrawable with said dog through the inner pipe.

ERNEST L. BARKER.
